CLAIM

The ornamental design for a circuit board as shown and described.

DESCRIPTION

FIG. 1 is a front elevational view of a circuit board showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a front, top, and right side perspective view thereof; and,

FIG. 8 is a front, bottom, and right side perspective view thereof.

The broken line showing of the circuit board is for the purpose of illustrating portions of the article and forms no part of the claimed design.
